UNITED STATES PATENT OFFICE.

RUDOLPH WITTGENFELD, OF CINCINNATI, OHIO, ASSIGNOR OF ONE-HALF
TO FREDERICK C. WEBER, OF SAME PLACE.

DESIGN FOR A BOTTLE AND GLASS TRAY FOR COUNTERS.

SPECIFICATION forming part of Design No. 23,899, dated December 25, 1894.

Application filed October 29, 1894. Serial No. 527,350. Term of patent 14 years.

To all whom it may concern:

Be it known that I, RUDOLPH WITTGENFELD, a citizen of the United States, and a resident of Cincinnati, in the county of Hamilton and State of Ohio, have invented a certain new and useful Design for Bottles and Glass Trays for Counters, of which the following is a specification.

My invention is a design for bottles and glass trays for counters, the distinguishing features of which are the rectangular frame supported upon ornamental scroll legs or standards, said frame apparently supporting the glass tray and bottle box, the edges of said tray and box folding over the edge of the frame and their adjacent edges folding over each other, as illustrated in the accompanying drawing, which is a perspective view of one end of the tray.

The frame, A, is rectangular, composed of side and end rails, consisting of the vertical web, a, and the laterally projecting flange, a', capping the web. This frame is supported by legs, B. The legs are arranged in pairs opposite each other, and connected by transverse braces, b, which have notched shields at their opposite ends abutting against the inside faces of the plain shields, b', which apparently strengthen and brace the metal scroll

members of the supporting legs. The legs or supports are of light flat bands formed in ornamental scroll work, as shown in the drawing. The bottle tray, C, has its front edge folded over to lap around the cap, a', of the side rails, and at its rear has an upwardly projecting back springing from the rear curved portion and meeting a bracket, d, which projects up from the rear edge of the drainer, D.

The drainer, D, has its sides and rear end curved around, and the bottom depressed between the frame formed by the folded end and sides, the bottom being formed in corrugations parallel with the sides of the drainer frame. The inner edge of the drainer frame meets or overlaps the folded edge of the tray, C, and its end is supported upon brackets, d', which rest upon the top of the frame, A.

What I claim as new, and desire to secure by Letters Patent, is—

The design for a bottle and glass tray for counters, substantially as shown and described.

RUDOLPH WITTGENFELD.
